United States Patent Office.

CARL FRIEDERICH ZIMMERMANN, OF PHILADELPHIA, PENNSYLVANIA.

Letters Patent No. 61,698, dated January 29, 1867.

STRAPS FOR ACCORDEONS.

The Schedule referred to in these Letters Patent and making part of the same.

TO ALL WHOM IT MAY CONCERN:

Be it known that I, C. F. ZIMMERMANN, of Philadelphia, in the county of Philadelphia, and State of Pennsylvania, have invented a new and improved Strap for Accordeons; and I do hereby declare that the following is a full, clear, and exact description thereof, which will enable those skilled in the art to make and use the same, reference being had to the accompanying drawing, forming part of this specification.

The drawing represents a perspective view of this invention.

This invention relates to a strap for accordeons, which forms a double loop, one to pass round the wrist and one to admit the thumb of the hand which grasps the accordeon, in such a manner that the strap is not liable to slip on the hand, and the player is enabled to operate the accordeon without danger of losing hold of the same.

Usually accordeons are provided with a simple loop of leather to receive the thumb of the right hand, by which the pulling and compressing of the bellows of the instrument are effected. This loop is insufficient to give to the player a firm hold of the instrument, particularly with large accordeons or flutinas, and it is utterly impossible to pass quickly from the deep to the high tones. The whole strain is brought to bear on the thumb, and the operation of playing a large instrument becomes very tiresome and difficult.

These disadvantages are avoided by my strap, A, which forms a double loop like the figure 8, one loop to pass over the wrist of the hand, and the other to admit the thumb, as shown in the drawing. This strap is secured to the instrument by a hinge joint, α , so as to leave its movements quite free, and the player is enabled to expand and compress the bellows without danger that the strap might slip, and furthermore he can move his hand freely from one end of the key-board to the other. The strain caused by the operation of the instrument is brought to bear on the wrist instead of on the thumb alone, and it is much easier to play an accordeon with one of my improved straps than it is to play the same instrument with the ordinary loop.

What I claim as new, and desire to secure by Letters Patent, is—

A strap for accordeons and other similar instruments, forming a double loop like the figure 8, substantially as and for the purpose described.

Also the combination of the hinge-joint α , with the strap, substantially as and for the purpose set forth.

The above specification of my invention signed by me this 5th day of July, 1866.

CARL FRIEDERICH ZIMMERMANN.
